CLAIM

The ornamental design for a plug adapter, as shown and described.

DESCRIPTION

FIG. 1 is a top view of a first embodiment of a plug adapter;
FIG. 2 is a bottom view thereof;
FIG. 3 is a left side view thereof;
FIG. 4 is a right side view thereof;
FIG. 5 is a front view thereof;
FIG. 6 is a rear view thereof;
FIG. 7 is a perspective view thereof;
FIG. 8 is a top view of a second embodiment of a plug adapter;
FIG. 9 is a bottom view thereof;
FIG. 10 is a left side view thereof;
FIG. 11 is a right side view thereof;
FIG. 12 is a front view thereof;
FIG. 13 is a rear view thereof; and,
FIG. 14 is a perspective view thereof.

The dashed broken lines and dash-dot broken lines in the drawings are for the purpose of illustrating portions of the plug adapter that form no part of the claimed design.

1 Claim, 14 Drawing Sheets
